DATA CONVERSION OPERATION
BOYERS, PA

113.

The Schedule referred to in these letters patent, and making part of the same, containing
 a Description in the words of the said Jacob Perkins himself of an improvement in the
 mode of manufacturing Nails &c. A short and general description of Jacob Perkins's
 Invention. I have invented and discovered a mode of making Nails by which much manual
 labor may be saved by means of an Engine, or revolutionary cutting Engine, and a
 Vulcan or heading Engine. The principle of the cutting Engine is that of a revolutionary motion in
 i.e. a roller with 2 cutters fixed in it to the circumference of the roller apart, which passing by another
 die in a standard or plate, cuts or pinches off what may be placed between either of the dies on the
 roller, and the die in the plate, directly above which is an aperture or slot, sufficient force of flat
 iron to pass this. the roller being turned in a skew shape tho' exceedingly true, acts always a guide
 to the shifting place, and brings it in that direction with each die in the roller, so as to cut up the
 whole strip of iron without any manual assistance, after it is once put in the aperture of the
 shifting plate. the heading Engine is worked by the revolution of a tappet wheel, having three tappets
 each of which lifts up a hammer, which gives three strokes each revolution of the wheel, on the anvil
 which is fixed in a Vice directly under the hammer. the three strokes forming the head of the nail.
 There is also affixed to the tappet wheel, a piece in a curved form, which catching the tail of the
 nail from the jaws of the Vice causes it to hold the nail sufficiently firm for the purpose of heading
 it. when the curved piece causes to operate on the Vice-lever, a spring pulls open the Vice-lever
 which turns, and the tappets again reaching the tail of the nail, another nail is put in; the hand
 nail dropping down immediately on the jaws of the Vice opening. It is to be observed one
 cutting Engine may with ease be drove by Water 250 revolutions in a minute each rotation
 produces 2 Nails & one Boy often or twelve years of age can with ease supply six Engines
 so that the labor of one Boy can cut three thousand Nails per minute, the heading
 Engine will head forty Nails per minute, by the assistance of one Boy, or more if it be
 possible for the Boy to hand them. a more particular description of these Engines
 is given in the Specification accompanied with drawings and written references being
 presented. And I the said Jacob Perkins do now and certify that this Schedule
 contains a short and general description of my invention as specified in the petition by
 me presented to the Secretary of State praying that letters patent may issue for
 the same according to law. Jacob Perkins
